UNITED STATES PATENT OFFICE

GUSTAVE M. NELL, OF DETROIT, MICHIGAN, ASSIGNOR TO CHICAGO PNEUMATIC TOOL COMPANY, OF NEW YORK, N. Y., A CORPORATION OF NEW JERSEY

SPIKE DRIVING APPARATUS

Application filed April 12, 1929. Serial No. 354,514.

This invention relates generally to the securing of flanged elongate members to supports by means of driven securing members. It has particular application to the spiking of railway rails to the cross members, or ties.

Hand methods in use in railway construction and repair work are slow, require a large gang of laborers and, even with skilled or experienced workers, result in a considerable percentage of poorly driven spikes. Moreover, when driven by hand the spikes are generally at a greater or less distance from the rail and the last few blows are directed toward bending the head of the spike toward and upon the flange of the rail. This leaves a space at one side of the spike into which water seeps causing softening and rotting of the wood so that the spikes become loose in a relatively short time. Spikes driven straight in are found to have much greater holding power and leave no spaces where water may gather.

In my improved method, one man with a power tool goes ahead and accurately "spots" or makes a guide hole in the tie for the spike close to the flange of the rail and at the proper angle so that when the spike is driven straight in the head of the same will have the maximum bearing or engagement on the flange of the rail. Another man follows with a second power tool, rests it loosely upon the head of a spike inserted in the previously made guide hole and drives it straight home. The punch for making the guide hole is tapered to permit its easy extraction and has limiting stops which engage the tie and not the rail flange. The hammer tool used in the driving operation has a retaining rim to hold the same on the spike but does not contact the rail flange at any time.

The method and the hammer tool are claimed in my copending application Serial No. 493,283, filed November 4, 1930, which is a division of this application.

One object of the invention is to devise suitable apparatus capable of use with a power tool for carrying out the above method. Another object is to provide a punch having a shank arranged for insertion in the

power tool to drive holes of proper depth closely adjacent the rail flange without injury to the latter. Other objects will be apparent from the detailed description which follows.

55

In order to illustrate the invention and the manner in which it is practiced, reference is to be had to the accompanying drawings, in which:

Fig. 1 is a pictorial illustration of the method as applied to spiking railway rails;

Fig. 2 is a fragmentary sectional view substantially on the line 2—2 of Fig. 3 showing the operation of the punch;

Fig. 3 is a side elevational view of the parts shown in Fig. 2 with the rail in section;

Fig. 4 is a view similar to Fig. 3 illustrating the hammer tool in place on the spike which has been inserted in the guide hole made by the punch in Figs. 2 and 3;

Fig. 5 is an enlarged elevational view of the punch;

Fig. 6 is a fragmentary view of the point of the punch shown in Fig. 5 after a quarter turn of the same; and

Fig. 7 is an elevational view partly in section of the hammer tool.

75

Fig. 1 illustrates the application of the method to the spiking of a rail A to cross ties B. Laborer X is operating a percussive power tool 8, such as a pneumatic hammer drill, which has inserted therein as a working tool a punch 9 for making guide holes for the spikes adjacent the edge of the supporting flange of rail A. After the holes are made spikes are inserted and a second operator Y follows with a similar percussive power tool 10 which has inserted therein as an operating element a hammer tool 11 which is placed upon the head of spike C and the latter is driven home until its head engages the flange of the rail.

The form of the punch is illustrated in Figs. 5 and 6 and the manner of its use is more clearly seen in Figs. 2 and 3. Punch 9 may be made of round stock as shown and is provided at one end with a polygonal shank 9a for insertion into a percussive tool, such as 8, and, if desired, with a retaining collar 9b. The other end of the tool is made to conform

substantially to the shape of a spike. Accordingly it is slabbed off or cut away to form oppositely directed faces 9c and similarly cut away after a 90° turn to form faces 9d. By preference this portion of the punch is substantially square in cross section and the faces thereof are all on a slight taper to permit easy extraction of the punch. Near the extreme outer end faces 9c have a sharp taper 10 9c' forming a wedge point. The faces 9c exceed in extent the faces 9d with the result that stop projections are formed at 9e. In using the punch these stops are arranged to engage the tie with the result that the greater 15 extent of the faces 9c prevent the punch from contacting and damaging the rail flange.

In operating machine 8 with punch 9 there- 20 in one of the tapered faces 9c' is placed directly against the flange of the rail (Fig. 1) with machine 8 held upright. As the point of the punch penetrates the wood the operator X shifts the tool 8 substantially to the inclination of tool 10 (supported by operator Y) so that the punch drives into the tie B substan- 25 tially at the angle shown in Fig. 3 until stop shoulders 9e engage the tie (Figs. 2 and 3). No damage can be done to the rail flange since it is clear from Fig. 3 that the extent of the faces 9c is such as to prevent engagement of 30 the body of the punch with the rail flange. Operator X now withdraws the punch, an operation made easy by the tapering of the faces forming the point. A spike C is dropped into the hole made by punch 9 and then 35 operator Y applies to the head of the spike the hammer tool 11 (Fig. 7) which has a polygonal shank 11a and retaining collar 11b to enable the same to be mounted in percussive machine 10. Hammer tool 11 is formed with 40 an enlarged head 11c provided with a socket having a concave impact wall 11d shaped to fit more or less closely the head of spike C and has a retaining rim or flange 11e to prevent the accidental slipping of the tool off the 45 spike. Rim 11e is of less vertical extent than the head of spike C so that as operator Y causes machine 10 to drive spike C home there is no contact between the hammer tool and the rail flange.

50 From the above it will be apparent that the herein described apparatus provides for the making of a guide hole for a securing member at exactly the proper position close to the flange to be engaged and at the right inclina- 55 tion, that the guide hole may be positively limited to such depth as will insure the maintenance of the desired inclination and the supporting of a heavy percussive tool for driv- 60 ing the retaining member, that with such a guide hole the securing of the hammer tool to the spike is unnecessary and that in both hole forming and spike driving injury to the flange of the member to be secured is avoided since in neither instance can the flow of the 65 percussive motor be transmitted directly to

the rail flange either through the punch or through the hammer tool.

I claim as my invention:

A punch formed at one end with a shank for insertion into a power operated percussive 70 machine, the portion of the punch remote from said shank being cut away in planes at right angles to one another to form a penetrat- 75 ing portion substantially square in cross section, the cut away portion on two opposed sides being of greater extent than on the two other sides thereby to provide advance pro- 80 jections for limiting the penetration of said punch.

Signed by me at Detroit, in the county of 80 Wayne and State of Michigan, this 8 day of April, 1929.

GUSTAVE M. NELL.
